UNITED STATES PATENT OFFICE.

HENRY M. SIEGEL, OF MELDEN, MASSACHUSETTS.

TROUSERS SUPPORTER.

Application filed July 7, 1926. Serial No. 120,942.

The invention has relation to trousers supporters of the class in which the essential element of a trousers supporter is a strap which, in the use of the device, is applied to the waist-portion of a pair of trousers through connection with the said portion at opposite points, and by means whereof the waist-portion may be constructed around the waist of the wearer; that is to say, above his hips, so as to hold the garment up properly. Usually, a device of the class in question has provisions for adjustment of the effective length of the strap, to suit the girth of the wearer and accommodate variations in the proportions of the garment, so that the waist-portion of the trousers may be made to fit with the requisite snugness and comfort.

The invention consists in a trousers supporter of the said class of improved and novel construction. The features of such trousers supporter provide in convenient and practical manner for ready adjustment and detachable connection of the device in working relations with the waist-portion of trousers.

An illustrative embodiment of the invention is shown in the drawings.

Fig. 1 of the drawings is a view on the order of a perspective of the said embodiment.

Fig. 2 is a top edge view thereof.

Fig. 3 is a view on the order of a perspective showing the said embodiment combined with the waist-portion of a pair of trousers.

Having reference to the drawings,—

The trouser-supporter shown therein comprises, as in the case of other devices of the same class, a flexible strap 1 and end-connectors 2, 2. With such parts I combine in distinctive manner one or more intermediate devices 3, 3, having the conjoined functions of adjustment-means and connectors. The strap 1 preferably is composed of a strip of elastic webbing as heretofore in some instances, although it may be composed of inelastic material. The end-connectors 2, 2, are attached to and carried by the strap. In this instance they are in the form of open links having key-hole shaped slots 21, 21, to enable them to be passed over and engaged with buttons 4, 4, Fig. 3, or equivalents thereof, attached to the waist-portion of a pair of trousers 5. Usually, the trousers-supporter will be applied and worn within the garment, and usually, therefore, the buttons 4, 4, or equivalent means of engagement,

will be mounted upon the inner side of the said waist-portion. The said end-connectors 2, 2, are formed also with transverse slots 22, 22, through which the end-portions of strap 1 extend. The said end-portions bend back around the cross-bars 23, 23, of the end-connectors, and to their extremities are attached the intermediate combined adjustment-means and connectors 3, 3, as shown in Fig. 2. The said devices 3, 3, are formed with loops 31, 31, which embrace the intermediate portion of the strap 1, and are consequently in sliding engagement therewith. Such sliding engagement provides for adjustment of the effective or working length of the strap, which is effected through sliding the members 3, 3, along the intermediate portion of the strap, toward or from the end-connectors 2, 2, as the case may be. In order to provide for maintaining the adjustment of the effective length of the strap, the members 3, 3, are constructed for engagement with the garment. In this embodiment of the invention such members are provided with safety-pin engaging means 32, 32, which in the use of the trousers-supporter are engaged in the material of the waist-portion of the trousers, as in Fig. 3. As will be perceived, adjustment of the effective length of the strap is effected by sliding one or both of the members 3 toward or from the corresponding end-connector or end-connectors, and the adjustment is maintained by engaging the safety-pin device or devices 32 with the garment. In the making of the said adjustment the loops 31, 31, of the intermediate connectors slide upon the said portion of the strap, but keep the intermediate connectors in proper working relations with the strap in all positions of adjustment, during wear of the trousers-supporter. The intermediate connectors 3, 3, hold the extremities of the strap and the intermediate portion thereof close together, while they also engage with the waist-portion of the garment to hold the intermediate portions of the strap in place against the garment.

The engagement of the end-connectors with the buttons 4, 4, at opposite points on the interior of the waist-portion of the trousers, and of the intermediate combination adjustment-members and connectors with the said waist-portion at intermediate points, combines the trousers-supporter with the garment in proper working relations. The said members 3, 3, hold the intermediate por-

tion of the strap from either dropping too low or rising too high, and they also enable the trousers-supporter to keep the intermediate part of the waist-portion of the trousers under proper control.

If it is desired to simplify the construction, one of the intermediate members 3 may be omitted, in which case the strap-extremity which is not equipped with such a member 10 will be engaged fixedly with the corresponding end-connector 2.

What is claimed as the invention is:—

1. In a trousers supporter comprising a flexible strap, and end-connectors adapted 15 for detachable engagement with engaging members carried by a garment at opposite points, with at least one end-portion of the strap in looped and sliding engagement with the corresponding end-connector, the combination with the said elements of an intermediate member which is fastened to the extremity of such end-portion, said member having a loop encircling the intermediate portion of 20 the strap and having, further, means for fastening it fixedly in lengthwise adjusted position to the garment.

2. In a trousers supporter comprising a

flexible strap, and end-connectors adapted 30 for detachable engagement with engaging members carried by a garment at opposite points, with at least one end-portion of the strap in looped and sliding engagement with the corresponding end-connector, the combination with the said elements of an intermediate member which is fastened to the extremity of such end-portion, said member having a loop encircling the intermediate portion of 35 the strap and having, further, means for fastening it fixedly in lengthwise adjusted position to the garment.

3. A trousers supporter comprising a flexible strap, end-connectors in sliding connection therewith adapted for detachable engagement with a garment at opposite points and from which the strap-extremities are bent back upon the strap itself, and combination adjusting and connector-members fastened to the extremities of the return portions of the strap, the said members having loops encircling the strap, and such members also having means for engaging the garment and thereby fixing said members and 50 the strap-extremities in lengthwise adjusted positions.

HENRY M. SIEGEL.
